US00D881079S

(12) **United States Design Patent** (10) **Patent No.:** **US D881,079 S**
(45) **Date of Patent:** **** Apr. 14, 2020**

(54) **VEHICLE FRONT LOWER GRILLE**

(71) Applicant: **Ford Global Technologies, LLC**,
Dearborn, MI (US)

(72) Inventors: **David Dewitt**, Docklands (AU); **Todd Willing**, East Melbourne (AU); **Max Wolff**, Birmingham, MI (US); **Pedro Guarinon**, Melbourne (AU)

(73) Assignee: **Ford Global Technologies, LLC**,
Dearborn, MI (US)

(**) Term: **15 Years**

(21) Appl. No.: **29/659,480**

(22) Filed: **Aug. 9, 2018**

(51) LOC (12) Cl. **12-16**

(52) U.S. Cl.

USPC **D12/163**; D12/171

(58) **Field of Classification Search**

USPC D12/163, 169, 196, 184
CPC B60R 19/52; B60K 11/08; B62D 25/08;
B62B 9/16
